SYNCHRONIZING DEVICE FOR TELEVISION SYSTEMS

Peter Deserno, Berlin, Germany, assignor to C. Lorenz Aktiengesellschaft, Berlin-Tempelhof, Germany, a company

Application March 29, 1940, Serial No. 326,566
In Germany March 18, 1939

4 Claims. (Cl. 178—69.5)

This invention relates to electrically operated devices for producing the synchronizing impulses employed in television systems. The pulsations for scanning line and picture synchronization must accurately synchronize while being perfectly in phase with each other. The requirement as to phase coincidence is important especially with the method of interlaced scanning. According to this method each picture is scanned in two groups of lines, each group taking the period of $\frac{1}{50}$ of a second, and the lines of one group are located between those of the other group. In this way, a complete picture will be transferred in $\frac{1}{25}$ of a second.

As is well known, synchronizing impulses may be produced with the aid of discs provided with holes. It has been found, however, that the accuracy obtained in this way is far from sufficient.

Another possibility resides in producing the pulsations electrically. The scanning line impulses may be obtained from the picture impulses. To such end, the sinusoidal public mains frequency may be multiplied and, for instance, the third or fifth harmonic filtered out therefrom and amplified. A second stage acts to filter one harmonic from the new frequency so obtained. By means of stages interconnected in cascade such multiplication may be continued so far that the scanning line frequency of $220.5 \times 50 = 11025$ hertz or cycles per second results from the mains frequency. The two pulsations so produced synchronize with each other. There is, however, no stable phase relation between them because any slight change in the form of the initial frequency causes the new frequency, derived therefrom by the said multiplication, to undergo a considerable phase displacement.

A method is known in which the picture impulse and the scanning line impulse are produced from an initial or main frequency by subdividing this. Such method, however, is useful to a certain extent only.

In order to explain this method reference is had to the schematic representation designated Fig. 1a in the accompanying drawings. The invention is thereafter described with reference to Figs. 1a, 1b, 2 and 3, of which

Fig. 1b is a graph illustrating the function of arrangements as provided by the invention, Fig. 2 is a circuit diagram that shows one embodiment thereof, while Fig. 3 is a graphical representation referred to in explaining the function of this embodiment.

As shown in Fig. 1a, also in this case stages

joined in cascade are employed. Each stage serves to effect a subdivision of frequency in the ratio 1:7 or 1:3, for instance, and acts in a manner similar to the well known saw-tooth current generators or relaxation devices. The relaxation in each stage is started by the preceding stage. As in this way the starting point is precisely predetermined the frequency obtained by the described stepped reduction of frequency not only synchronizes with the initial frequency but also is independent thereof as regards phase.

The initial or main frequency in the case of interlaced scanning is double the scanning line frequency and according to the standard now in use is 441 times the picture frequency. This initial frequency, produced by a generator X, serves to control both a generator Y, employed for producing the scanning line impulses, and the next following lower frequency of the frequency-reducing cascade. The cascade may comprise four stages, for example, as shown in Fig. 1a, the two first stages effecting a subdivision of frequency in the ratio 1:7 while the subdivision caused by the two last stages is in the ratio 1:3.

This method requires the picture gap alternately to occur one time in company with the line gap and then accurately to occur in the middle of the line. By means of the said frequency reduction, starting from the initial frequency generator X and effected with the aid of relaxation generators, the picture impulse of a frequency generator Z will be coupled with the scanning line pulsations in a manner to be sufficiently stable in phase. However, the starting of the picture impulse does not in any case coincide with that of the line impulse. The detrimental phase shift B so incurred arises in the cascade through periods of losses which occur when synchronizing the stages thereof.

In order to overcome this drawback the invention proposes to construct the initial frequency generator X as an impulsive device for producing impulses whose width is regulable.

In Fig. 1b, V denotes the up-slope or "front flank" of the impulses produced by generator X, while R designates the down-slope or "back flank." The flank V is used for synchronizing the first stage of the frequency-reducing cascade, whereas flank R is to synchronize the line impulse generator Y.

The distance B between the flanks V, R is made to equal the phase shift that occurs in the cascade. For instance, distance B may be adjusted by varying a resistance. As in this case also the frequency of the generators is liable to

change, an additional variable means, adapted for readjusting the frequency, may be provided. This variable means and the said variable resistance, or other appropriate contrivances may be coupled together by suitable mechanic or electric means in a manner to ensure that the frequency remains constant despite varying the distance between V and R.

In the arrangement shown in Fig. 2 the initial frequency generator X and the line impulse generator Y are multi-vibrators of a known circuit connection. The curves illustrating the grid and anode voltages are represented in Fig. 3. U_{a1} and U_{g1} relate to the tubes 1, 1', of the two multi-vibrators, while U_{a2} and U_{g2} refer to the tubes 2, 2'. By means of the flank V of the impulse of U_{g2} the first stage of the frequency-dividing cascade may be synchronized over C_1 . The same impulse when imparted over C_2 to the grid of tube 1' of the generator Y causes this generator to be controlled by means of flank R. The distance B between the flanks V, R is given by the magnitude of the elements C_k and R_k of generator X. If for varying the distance B the resistance R_k is increased the curve E is flattened, as indicated by curve E'. In consequence of the fact that the rise of the grid voltage is delayed in this way the period at the end of which the relaxation effect of the tube occurs is increased. As a result also the distance B is enlarged. At the same time the frequency of the multi-vibrator is decreased, as the time constant is greater than before. The original frequency may now be obtained by diminishing the resistance R_k accordingly. The flank V has a time lead, being in advance of the flank R by the amount B. By properly dimensioning the condensers C_k , C_g and R_k , R_g the frequency and

the distance B will be adjusted in a manner to compensate the phase displacement that arises within the cascade.

What is claimed is:

5. 1. In an arrangement for generating synchronizing impulses in television systems for the production of a picture at a certain picture frequency and at a certain scanning line frequency, means for generating an initial frequency equal to said scanning line frequency or to a multiple thereof, a generator for producing this initial frequency, a generator for producing said scanning line frequency, a cascade comprising stages for reducing said initial frequency by subdivision in steps, and means under control of said initial frequency for imparting to the first of said cascade stages and to the said scanning line generator a phase shift adapted to compensate for a phase displacement due to the said cascade.
10. 2. In an arrangement according to claim 1 and means for producing by means of the initial frequency generator impulses the graphic representation of which has steep flanks, the trailing edge of said impulses being used to synchronize the line oscillator and the leading edge to synchronize the frame oscillator.
15. 3. An arrangement according to claim 1, which comprises means for adjusting the width of impulses produced by the initial frequency generator.
20. 4. An arrangement according to claim 1, wherein the initial frequency generator is adapted to produce impulses the graphic representation of which has steep flanks, and wherein means is employed for maintaining the frequency of this generator constant despite variation of the distance between said flanks.

PETER DESERNO.
